US0D1074787S

(12) **United States Design Patent** (10) **Patent No.:** **US D1,074,787 S**
(45) **Date of Patent:** **** May 13, 2025**

(54) **EYE MASK**

(71) Applicant: **RELIVE CO., LTD.**, Sendai (JP)

(72) Inventor: **Takashi Sasaki**, Sendai (JP)

(73) Assignee: **Relive Co., Ltd**, Miyagi (JP)

(***) Term: **15 Years**

(21) Appl. No.: **35/518,109**

(22) Filed: **Apr. 29, 2023**

(80) **Hague Agreement Data**

Int. Filing Date: **Apr. 29, 2023**

Int. Reg. No.: **DM/230754**

Int. Reg. Date: **Apr. 29, 2023**

Int. Reg. Pub. Date: **Aug. 18, 2023**

(30) **Foreign Application Priority Data**

Nov. 22, 2022 (JP) ..... 2022-025290 D
Nov. 22, 2022 (JP) ..... 2022-025291 D
